SEWING MACHINE TABLE

Torine Charlotta Torines, Stockholm, Sweden

Application October 8, 1937, Serial No. 168,104
In Sweden February 5, 1936

10 Claims. (Cl. 312—30)

The present invention relates to table sewing machines of the type in which a desk-like or similar support for the machine is provided in its top with a well or recess into which the machine can be lowered when not required for use. The main object of the invention is to provide means whereby the treadle is automatically folded away, or brought into the operative position and positively connected to the driving means, when the machine is folded away, or brought into operative position, respectively.

A further object of this invention is to enable the leg space of the table which contains the treadle to be left unencumbered by the treadle when the machine is folded away so as to provide a neat and tidy desk-like table when the machine is not in use, and with none of the operating mechanism visible.

The invention is illustrated in the accompanying drawings, Figs. 1 to 7 showing one embodiment, and Figs. 8 to 11 showing another embodiment, and wherein:

Fig. 1 is a front perspective view of the sewing machine table folded to present the appearance of an ordinary table with drawers;

Fig. 2 is a front elevation view showing the sewing machine and the treadle ready for use;

Fig. 3 is a vertical sectional front view of Fig. 1;

Fig. 3A is a detail view of the upper left part of Fig. 3 on a larger scale;

Fig. 3B is a detail view of the lower left part of Fig. 3 on a larger scale;

Fig. 3C is a detail view of the lower right part of Fig. 3 on a larger scale;

Fig. 4 is a transverse vertical sectional view on line 4—4 of Fig. 3;

Fig. 4A is a detail view of the upper part of Fig. 4 on a larger scale;

Fig. 5 is a transverse vertical section on line 5—5 of Fig. 2;

Fig. 6 shows, on a larger scale, and in vertical section lengthwise of the table, the lower part of the table with the treadle in swung down position;

Fig. 7 is a horizontal sectional plan view of Fig. 6;

Fig. 7A is a detail view on a larger scale of some of the parts in Fig. 7 with the parts in inoperative position corresponding to Fig. 3C;

Fig. 8 is a vertical longitudinal section of the sewing machine table;

Fig. 9 is a horizontal section of Fig. 8;

Fig. 10 is a vertical transverse section on line 10—10 of Figs. 8 and 9; and

Fig. 11 is a fragmentary vertical section of the

treadle parts, on a larger scale on line 11—11 of Fig. 9.

Referring to Figs. 1 to 7 of the drawings the head of the sewing machine table is indicated by the reference numeral 1 and is provided with two drawers, the sewing machine 2 being swung into the concealed position in the head 1. Within the head is provided means for supporting the sewing machine 2 so that it can be swung down from the position illustrated in Fig. 2 and Fig. 5 to the position below the top surface of the head 1, as shown in Figs. 1, 3 and 4. The rear edge of the base plate 7 of the sewing machine is connected by means of hinges to the head 1, and the front edge of the sewing machine base 7 rests on a projection 15 on a movable flap 35 when the machine is in use. When the sewing machine is to be folded down below the table top so as to depend from its said hinges, the flap 35 is first swung upwards in known manner, so that its projection clears the 20 front edge of the base plate 7, and the sewing machine is then lowered within the head 1. In this position the recess of the head concealing the machine 2 may be covered by a panel 36. An arcuate plate 6 is pivoted at its ends link fashion 25 to coiled tension spring 26 and to a part of the head 1 to act as means for limiting the downward swing of the machine to the angle which brings the base plate 7 to the vertical depending plane as shown in Figs. 4 and 4A. The springs raise the 30 arcuate plate 6 when the machine 2 is raised to the operative position. A treadle 4 for operating the sewing machine is located near the floor between the two box-like side members 1a and is connected at one end by two hinges 23 to an oscillating plate 19 (Figs. 3B and 6), so that it can be 35 swung to the vertical plane position shown in Figs. 1, 3 and 4 closing the inner side wall of the left hand (looking at Figs. 2 and 3) box-like part 1a. The oscillatable plate is supported by a foot bearing 21 comprising two supports 21a and one member 21b mounted between the supports to oscillate about the axis 21c (Fig. 3B). The oscillatable plate 19 is fixed to the member 21b and is thus oscillatable lengthwise of the treadle 4. 40 When the treadle is folded upwards the foot bearing 21 is concealed.

In the other box-like side member 1a is accommodated a driving wheel 3, the bearing 3a of which is fixed to the outer wall of the appropriate 50 side member 1a. The usual connecting rod 5 connects the wheel 3 to an oscillatable plate 20 similar to the plate 19 and supported on a foot bearing 22 comprising two supports 22a, one oscillatable member 22b and an axis 22c (Fig. 3C) in similar- 55

ity with the bearing 21. The customary belt 3b passes around the driving wheel 3 and a pulley 2a of the machine.

The treadle 4 is automatically swung to the folded and operative positions contemporaneously with the corresponding adjustments of the sewing machine. For this purpose, attached to the side edge of the base plate 7 which is the lower when the machine is folded, is one end of an angle iron 8 (see Figs. 3, 3A and 4). The other end of the angle iron 8 is fixed to a shaft 9 supported just below the table top by two bearings 10 and to this shaft 9 is fixed one end of an arm 11 the other free end of which carries a roller or pulley 12 which bears upon the horizontal upper central part 13a of an inverted U-shaped member 13 slideable in lugs 14 fixed to the inner wall of the appropriate box like member 1a. Coiled tension springs 27 tend to raise the U-shaped member 13. The lower ends of this member 13 are pivotally connected to a pair of links 15 (see Fig. 3) which are cranked towards each other as at 15a to bear against a pair of arcuate bars 18 (shown in Figs. 3 and 3B and in broken lines in Fig. 6) when the machine is folded away. These links 15 are formed with wedge-like projections 17, and the inner wall of the appropriate box-like member 1a is likewise formed with an oppositely directed pair of wedge-like projections 16, or there may be a single wide wedge-like projection. These opposed wedge-like projections 16 and 17 direct the links 15 downwards and outwards when the U-shaped member 13 is pushed downwards against the influence of the springs 27. The arcuate bars 18 are fixed to the treadle 4 and act as arms receiving the downward pressure of the links 15 to raise the treadle 4 to the folded vertical position.

When it is desired to fold away the sewing machine, the machine is first lifted a little upwards at the front edge of the base plate 7 resulting in the flap 35 also being turned upwards, whereupon the sewing machine 2 is lowered into the head 1. The base plate 7 of the sewing machine is now turning on its hinges and at the same time swinging the arcuate plate 6 downward, resulting in the angle iron 8 rotating the shaft 9, whereby the member 11 is subjected to turning. The pulley 12 on the member 11 now presses down the U-shaped member 13, and the links 15, whereby the lower end parts of the levers 15 are pressing on the arcuate bars 18, which latter swing the treadle to the vertical position. When the sewing machine 2 is swung up to the operative position an opposite swinging of the treadle 4 from the vertical to the horizontal position automatically takes place. By this means there are no obstructive parts beneath the head or table 1, and also the machine is obscured by a flap 35 neatly filling the opening through which the machine swings. A movable panel 24 obscures the driving wheel and associated mechanism when the machine is not in use, this panel 24 being slideable in a vertical plane. The upper end of this panel 24 is connected by a pair of coiled tension springs 25 to the head 1 and to the flap 35 respectively. These springs tend to raise the panel 24 but a limit to the raising movement is set by the lower surface of the plate 6 which engages the upper edge of the panel 24 (compare Figs. 4 and 5). It is seen therefore, that in the position according to Fig. 4 the panel 24 will be pressed downwards to close one side member 1a, but in the position according to Fig. 5 the springs 25 may act to maintain the panel in a raised position, making the mechanism available. Secured to the flap 35 is the upper end of a rope 34

the lower end of which is carried under a fixed guide pulley 33 and ultimately secured to an eye 28b of a U-shaped member 28, the extremities of which are shaped as forks 28a adapted to embrace the appropriate end of the treadle 4 when the treadle is in the operative position as shown in Figs. 5, 6 and 7. The fork 28 is guided for horizontal sliding movement by a pin 32 and slot 31, and two longitudinal channels 39 in the oscillatable plate 20. The U-shaped member 28 is urged outwards against the appropriate edge of the treadle 4 by means of a spring 29, shown in Figs. 3C, 5, 7 and 7A. The ends of this spring are fixed to pins 28a, 28b at the plate 28 and the central portion of the spring engages the eye 28b of the member 28. The U-shaped member 28 is adapted to hold the treadle 4 in horizontal position at its free end in firm connection to the oscillatable plate 20. The U-shaped member 28 is thus automatically engaged with the free edge of the treadle 4, so that, when the sewing machine is turned upwards, the flap 35 must first be raised, whereby a pull on the rope 34 takes place, thereby drawing the U-shaped member 28 into the drawer case, thus enabling the free end of the treadle 4 to be lowered into the horizontal position without engaging the forks 28a. When the sewing machine reaches the raised position, the flap 35 is lowered, whereby the tension on the rope 34 is released and the forks 28a pushed by the springs 29 into locking engagement with the treadle. When lowering the sewing machine below the table top the reverse operation takes place, i. e., at first the forks 28a disengage with the appropriate edge of the treadle 4, thus enabling the automatic raising of the treadle and subsequently the U-shaped member 28 is moved to its outermost position by the springs 29.

In the modification illustrated in Figs. 8, 9, 10 and 11 the spring leaded U-shaped member 13 is guided between bars 37. The lower end of the U-shaped member 13 is connected to one end of a pair of links 38, the other ends of which links are formed with square holes 39 adapted to receive square ended pins 40 on a transverse shaft 41 on the treadle 4. The links 38 are connected by bosses at their apertured parts 39 to the lower end of a pair of arms 43 pivoted at their upper ends to lugs 42 fixed to the member 1a, and the lower ends of these arms 43 are apertured to slide upon the ends of a horizontal tube 45 supported at its ends in bearings 44. Coiled compression springs 46 are interposed between the arms 43 and abutments 46 on the tube 45.

The limbs of the U-shaped member 13 are resilient to enable them to be moved towards each other by reason of the tension applied to the rope 34 which is anchored at one end to a screw 50 threaded into one of the arms 43 within the tube 45 and passed over a pulley 48 secured within the lower end of the other arm 43. The screw 50 and the pulley 48 slide in slots 49 in the tube 45. A pair of opposed fixed angle bars 51 serve as abutments against which the lower ends of the U-shaped member 13 are pressed when in their lowest position in order to maintain engagement of the square pins 40 and the square holes 39. The end of the treadle remote from the oscillatable plate 20 is formed with a pivot 52 detachably engaged in lug 53.

When the rope 34 is drawn upwards by the flap 35, the rope draws the links 38 towards each other whereby the end pins 40 on the shaft 41 enter the holes 39 and when the base plate 7 forces down the fork 13 when the machine is lowered, the links 38

swing the treadle 4 upwards into the vertical plane as shown in broken lines in Fig. 8. When the base plate 7 is swung upwards to the operative position, the U-shaped member 13 is drawn upwards by means of the springs 27 whereby the links 38 assume their upper position as shown with the full lines in Fig. 8, so that the links 38 are disengaged from the abutments 51 and the springs 47 press the links 38 apart, disengaging them from the pins 48, thus releasing the treadle into the operating position.

What is claimed as new is:

1. In a sewing machine table, the combination of an approximately horizontal top section including a movable sewing machine supporting member adapted to be moved from a position in which the sewing machine is in operative position to a position in which the sewing machine is in inoperative position; two spaced side sections supporting said top section at opposite ends thereof respectively; a sewing machine actuating treadle adapted to be moved to an inactive upright position in close relationship to one of the side sections, or to an active approximately horizontal position in the space between the side sections; and connecting means between said sewing machine supporting member and said treadle whereby said treadle is automatically moved to its inactive upright position when said sewing machine is moved to its inactive position.

2. In a sewing machine table, the combination of an approximately horizontal top section; two spaced side sections supporting said top section at opposite ends thereof respectively; a sewing machine actuating treadle adapted to be moved to an inactive upright position in close relationship to one of the side sections, or to an active approximately horizontal position in the space between the side sections; a sewing machine mounted on said top section and movable from an operative position above the table top to an inoperative position below the same and vice versa; and means controlled by said movement of the sewing machine to its inoperative position to move said treadle to its inactive position.

3. In a sewing machine table, the combination of an approximately horizontal top section including a movable sewing machine supporting member adapted to be moved from a position in which the sewing machine mounted thereon is exposed and in operative position, to a position in which the sewing machine is enclosed within said top section and in inoperative position; two spaced side sections supporting said top section at opposite ends thereof respectively; a sewing machine actuating treadle adapted to be moved to an inactive upright position in close relationship to one of the side sections, or to an active approximately horizontal position in the space between the side sections; and connecting means between said sewing machine supporting member and said treadle whereby said treadle is automatically moved to its inactive upright position when said sewing machine is moved to its enclosed inactive position.

4. In a foldable sewing machine, a table top part supporting and accommodating the machine; a box-like side part serving as a supporting leg for the table top; a swingable treadle hinged at one end portion to the said box-like part; a transmission mechanism within the box-like part arranged for transferring the folding and unfolding movements of the machine to the treadle in such a manner that, when the machine is folded into the table top, the treadle is auto-

matically swung from an operative approximately horizontal position to an approximately vertical position, in which the treadle enters the inner space of the box-like part and forms the inner vertical wall of the latter; a second supporting leg for the table top spaced from the box-like part; and journal means attached to the said second supporting leg and arranged for detachably supporting the free end of the treadle in the horizontal position.

5. Sewing machine according to claim 4, wherein in the hinged end of the treadle carries a lever-like extension projecting into the said box-like side part; means actuated by the fall of the sewing machine base actuating said lever to effect the raising of said treadle contemporaneously with the movements of the sewing machine base.

6. Sewing machine according to claim 4, wherein in the treadle is hinged at one end to an oscillatable member within the box-like side part, so that it may be swung relatively to the oscillatable member to and from the operative position, and the other end of the treadle is adapted to be automatically connected to and disconnected from another oscillatable member attached to the said second supporting leg, said latter oscillatable member actuating the means for driving the machine.

7. Sewing machine according to claim 4, wherein in the treadle is formed with front and rear projections adjacent its pivotally supported end adapted to receive co-operating locking elements urged away from said projections by spring means, said locking elements being operatively connected to a displaceable sewing machine supporting element in the table top and adapted when the sewing machine is folded downwards into the table top to be engaged with said projections by reason of the movement given to said displaceable element and to receive a partial rotary movement to swing the treadle to the vertical folded position.

8. The sewing machine according to claim 3, wherein the treadle is hinged to one side section and at the other side section engages an oscillatable member actuating the driving means for the machine, said member having locking means for slidable engagement with said treadle and spring means opposing disengagement therewith; and connecting means between said oscillatable member and the movable sewing machine supporting member whereby the locking member is engaged or disengaged from the treadle by the unfolding or folding movement respectively of said supporting member.

9. The sewing machine according to claim 4, wherein the transmission mechanism includes a vertical actuating member adapted to raise the treadle when said member is depressed by the folding movement of the table top part supporting the machine, said actuating member having slidable locking elements connected thereto; and a pair of abutments adapted to retain said locking elements in locked position when the treadle is raised.

10. The sewing machine according to claim 3, wherein the connecting means includes an arcuately movable member connected to the treadle and adapted to raise said treadle to folded position by the downward pressure on said member of a vertically slidable member in turn actuated by movement of the sewing machine supporting member.

TORINE CHARLOTTA TORINES.
